UNITED STATES PATENT OFFICE.

GRANVILLE A. HUMASON, OF HOUSTON, TEXAS.

PUMP.

1,380,476.

Specification of Letters Patent. Patented June 7, 1921.

Application filed January 20, 1920, Serial No. 352,660. Renewed December 4, 1920. Serial No. 428,380.

To all whom it may concern:

Be it known that I, GRANVILLE A. HUMASON, a citizen of the United States, residing at Houston, Harris county, Texas, have invented a certain new and useful Improvement in Pumps, of which the following is a full, clear, and exact description, such as will enable others skilled in the art to which it appertains to make and use the same.

10 My invention relates to an improvement in pumps and has particular reference to the plunger to be employed in reciprocating deep well pumps. It is an improvement on the pump shown in my Patent No. 1,325,565, issued December 23, 1919.

This type of pump is especially adapted for working in oil or water which is accompanied by more or less sand or grit tending to wear the working parts of the pump and especially the plunger and the working barrel adjacent thereto so as to quickly reduce their efficiency.

An object of my invention is to provide a pump plunger so constructed as to be expandable for the purpose of taking up wear which may occur without the necessity of removing the plunger from the well.

Another object is to so arrange the expanding parts connected with the plunger 30 that they will not expand except when desired and will then be expandable only to the amount required to take up the wear occurring in the operation thereof.

Another object is to provide a supplementary lifting means in connection with the plunger which will most efficiently assist in the raising of the fluid from the well.

Other objects and advantages will more clearly appear in the description which follows and will be set forth with particularity in the claims.

Referring now to the drawing wherein like parts are designated by like numerals of reference throughout the several views, 45 Figure 1 is a central longitudinal section through a pump barrel and plunger showing the construction of my invention; Fig. 2 is a similar section through the lower part of the pump barrel showing an elevational view 50 of the plunger; Fig. 3 is a transverse section on the line 3—3 of Fig. 1; Fig. 4 is a transverse section in the direction of the arrows on the line 4—4 of Fig. 5; Fig. 5 is a transverse section through the pump plunger and 55 working barrel of the pump showing a slightly modified form of plunger; and Fig.

6 is a transverse section on the line 6—6 of Fig. 5.

In the embodiment of my invention shown in Fig. 1 I have a working barrel 1 which is closed at the upper end at 2 and provided with a gland 3 through which the sucker rod 4 is adapted to reciprocate. At some point in the working barrel I place a diaphragm 5 to provide a closure across the working barrel for a purpose which will presently appear. In the drawing I have shown this diaphragm adjacent the upper end of the working barrel, said diaphragm being connected between two adjacent lengths of the working barrel and threaded exteriorly for connection with the coupling member 6. This diaphragm has a central opening 7 therethrough to accommodate the sucker rod which reciprocates therein, and has a plurality of downwardly opening valves 8 therein. These valves may be of any ordinary construction, but I have shown the usual flap valve pivoted adjacent the openings and held by springs 9 upwardly into closed position.

The plunger which constitutes the principal part of my invention comprises an upper head 10 which is reduced toward the lower end to provide a downwardly extending tubular portion 11 upon which the expanding means is adapted to seat. The expanding means comprises a sleeve 12 having a flat upper face 13 to contact with the lower shoulder of the head 10. Said sleeve 12 is of the full diameter of the head at its upper end at 14, but is recessed at 15 and tapered downwardly from said recess to the lower end thereof, thus providing a sleeve which is practically the shape of an inverted cone 95 and slidable upon the tubular member 11 of the head.

Fitting over the lower tapered portion of the sleeve 12 is a second expanding sleeve 16. This sleeve is split longitudinally into four parts in the manner shown in Fig. 6 and has a lower annular flange 17 thereon of the full diameter of the head and is recessed on its outer face at 18 to accommodate a series of expanding rings 19 thereon. 100 These expanding rings 19 are split at one point, as shown at 20 in Fig. 2, so that they may be expanded to take up wear. Adjacent the upper and lower of the expanding rings 19 are soft metal sealing rings 21. 110 These rings are not split and when first introduced into the pump barrel are slightly

smaller in diameter than is the head of the plunger itself.

At the lower end of the tubular member 11 of the head is threaded a cylindrical nut 22. This nut contacts with the lower end 5 of the expanding sleeve 17 and projects beyond the end of the tubular member for a distance sufficient to engage with a second nut 23 having an upwardly extending reduced portion 24 threaded exteriorly within 10 the nut 22. When the nut 23 is threaded originally into contact with the nut 22 a space is provided at 25 between the upper end 24 of the nut 23 and the lower end of 15 the tubular portion 11 of the head so that a further tightening of the nut may be accomplished. The nut 23 is provided with a tubular passage 26 therethrough for connection with the tubular section 11 of the head 20 so as to provide a passage upwardly for the fluid being pumped. A valve 27 is preferably formed in the passage 26 through the lower nut, this valve being shown as a ball valve, the ball of which is limited in its 25 upward movement by a cross pin 28 fixed in the lower end of the tubular member 11 of the head. The lower face of the nut 23 has a transverse notch or groove 29 by which the said nut may be turned when necessary, 30 it being contemplated that at some point in the lower portion of the working barrel a cross piece will be fixed against which this nut may be lowered and held against rotation for tightening the expanding sleeve 35 upon the head of the plunger.

The upper end of the head is formed with a reduced upwardly extending tubular portion 30 threaded interiorly for connection with an enlarged valve chamber 31, this 40 valve chamber accommodating a ball valve 32 limited in its upward movement by a cross bar or pin 33 in the usual manner. The upper end of the valve chamber is threaded interiorly to the lower end of the 45 sucker rod previously described.

The compression means described in my Patent No. 1,325,565, previously referred to, is employed in connection with this pump. This compression means includes the diaphragm 5 previously referred to and also 50 comprises an inlet means for the compressed fluid so that the same may be forced upwardly through the sucker rod 3 to assist in raising the liquid from the well. This fluid 55 may be compressed air, steam, water or other fluid pumped into the pump barrel through the laterally extending pipe 34 in the upper end of the said pump barrel. This compressed fluid is forced past the valves 8 in 60 the diaphragm 5 and downwardly into contact with the plunger. It there finds entrance through passages 35 which are formed in the upper end of the head 10 of the plunger extending diagonally downward 65 for connection with a short transverse pipe

36, the said pipe having an upwardly opening valve chamber 37 connected therewith. This valve chamber is shown as cylindrical in shape and is perforated by openings 38 therein. Said valve chamber accommodates 70 a cylindrical pin 39 which is tapered at the lower end at 40 for seating within the valve seat. The upper end of the valve 39 has a slightly enlarged head 41 which is tapered somewhat on its upper face and adapted to 75 rest on the upper end of the valve chamber 37. A transverse pin 42 limits the upward movement of the valve 39.

In the operation of my improved pump plunger the parts are assembled as shown 80 in Fig. 1. The diaphragm and upper portion 2 of the barrel are removed and the pump plunger is inserted within the pump barrel. The coupling 6 is then threaded in place and the diaphragm 5 and upper cap 85 2 are then placed in position. The sucker rod reciprocates fluid tight through the diaphragm 5 so that there will be no loss of pressure below the said diaphragm. The reciprocation of the plunger will itself act 90 to draw air or other fluid inwardly through the pipe 34 and past the diaphragm so that on the upward movement of the plunger the fluid will be compressed below the diaphragm and will be hence forced through 95 the passages 35 and 36, raising the valve 39 upwardly into contact with the pin 42, as shown in Fig. 5, thus allowing the fluid to escape through the openings 38 in the valve chamber and be projected upwardly through 100 the sucker rod 3. The valve 32 above the plunger is adapted to prevent too heavy a back pressure due to the head of water or oil within the sucker rod. When sufficient pressure is not automatically obtained by 105 the operation of the pump, steam or other compressed fluid may be forced downwardly past the diaphragm and further assist in lifting the fluid upwardly through the sucker rod in the manner just described. 110 The plunger is operated until wear is noted due to the presence of sand or grit between the plunger and the working barrel, it then becoming necessary to tighten the plunger within the barrel. This is done by lowering 115 the sucker rod until the notch 25 in the lower face of the nut 23 is seated upon a cross piece in the working barrel and the sucker rod and plunger are then rotated, thus acting to thread the tubular member 12 downwardly within the nuts 22 and 23. This serves to force the split ring 16 upwardly upon the tapered surface provided by the sleeve 12 and tends to expand the same. As the sleeve 16 is expanded the 120 metal rings 19 outside thereof are also expanded into close contact with the interior face of the working barrel this taking up the wear which has occurred. As the sleeve 16 is forced toward the sleeve 12 the soft 125 130

metal rings 21 are compressed between the end of the sleeves 12 and 16 and the metal rings and are flattened somewhat so as to fill the space between the sleeves and the 5 working barrel. A space 43 adjacent the upper ring 21 is provided to accommodate the flattening or lateral expansion of the rings at that end, the expansion of the lower ring being taken up by the wear against the 10 side of working barrel. The purpose of these soft metal rings is to prevent the movement of the sleeves 12 and 16 toward each other during the operation of the plunger and to hold them properly spaced apart. 15 Being of soft compressible metal, however, they are adapted to be flattened by the compression exerted by the nuts 22 and 23 thus allowing the metal rings or washers 19 to be expanded as desired.

20 In the modification shown in Figs. 4, 5, and 6, the parts there shown are practically identical with those disclosed in Figs. 1 to 3 inclusive with the exception of the expanding means upon the pump plunger. 25 The sleeve 12' is recessed somewhat more deeply at 15' to provide a seat for a helical spring 44 therein, a similar spring 44 finding a seat in the outer recessed face of the split sleeve 16. These springs are strong in construction and are shown as rectangular in 30 transverse section, thus tending to force the sleeves 12' and 16 apart and to prevent their being jammed together by the reciprocating action of the pump during the operation 35 thereof. It is clear, however, that the split sleeve 16 may be forced upwardly upon the sleeve 12', as previously described, thus compressing the springs 44 and expanding the rings 19. Without the springs 44 or the 40 soft metal rings 21 it is found that the strong reciprocating action of the plunger will act to force the sleeve 16 upwardly upon the tapered surface of the ring 12 and cause the expansion of the rings when this expansion 45 is not desirable and would tend to lock the plunger within the working barrel and perhaps cause a breaking of the operating parts. By the use of the spring 44 and of the rings 21, however, the expanding rings 19 will 50 preserve the desired diameter until they are positively expanded by the tightening of nuts 22 and 23 on the lower end of the plunger, in the manner described. The improvements thus disclosed in connection 55 with my invention are extremely important and together make up an operative device which will be positive in its action and simple in construction, thus producing a more efficient device.

Having thus described my invention, what I claim as new and desire to protect by Letters Patent is:

1. In a pump, a working barrel, a plunger reciprocable therein, said plunger comprising a tubular member, a conical sleeve thereon, a longitudinally divided expanding sleeve fitting on said conical sleeve, said expanding sleeve being recessed on its outer face and provided with a series of split rings and means between said rings and said sleeves in the upper and lower ends thereof to normally prevent the movement of said sleeves toward each other and means to expand said expanding sleeves and said rings when desired.

2. In a pump, a plunger, a tubular portion provided with a seat, a conical sleeve slideable thereon, a split sleeve fitting over said conical sleeve and said seat, a cylindrical recess on the outer face of said split sleeve and said conical sleeve, expanding rings in said recess, and soft metal rings in said recess between said expanding rings and the shouldered ends of said recess and adapted to be compressed when said sleeves are forced toward each other, and a nut on said tubular portion operative while in the pump barrel to force said split sleeve toward said conical sleeve.

3. In a pump, a plunger including a head, a reduced tubular portion thereon, a conical sleeve on said reduced portion and bearing on said head, a split sleeve fitting over said conical sleeve, expanding rings on said split sleeve, means to prevent accidental movement of said sleeves axially of said plunger and positive means to force said expanding sleeve axially of said conical sleeve and to expand said rings.

4. In a pump, a plunger, a tapered surface thereon, a split sleeve on said tapered surface, expanding rings on said split sleeve, means to normally prevent axial movement of said sleeve on said tapered surface and positive means to force said split sleeve into expanded position when desired.

5. In a pump, a plunger comprising a head, a reduced tubular portion, a nut on the lower end thereof, an expanding collar between said head and nut adapted to be expanded by the tightening of said nut, split rings on said collar and means to hold said collar normally against expansion.

In testimony whereof I hereunto affix my signature this the 15th day of January, A. D. 115 1920.

GRANVILLE A. HUMASON.
